UNITED STATES PATENT OFFICE.

HIRAM J. WATTLES, OF SYRACUSE, NEW YORK.

HEATING APPARATUS.

SPECIFICATION forming part of Letters Patent No. 661,629, dated November 13, 1900.

Application filed June 16, 1899. Serial No. 720,745. (No model.)

To all whom it may concern:

Be it known that I, HIRAM J. WATTLES, of Syracuse, in the county of Onondaga, in the State of New York, have invented new and 5 useful Improvements in Heating Apparatus, of which the following, taken in connection with the accompanying drawings, is a full, clear, and exact description.

My invention relates to heating apparatus; 10 and my object is to produce an improved hot air, hot water, or steam heater or producer comprising a fire-box, a zigzag smoke-flue above the combustion-chamber, a chamber for hot air, water, or water and steam above 15 the combustion-chamber subdivided by the passage of the members of the smoke-flue through it, each of these members having heating-surface substantially equal to the areas of the faces of the compartments of the 20 air-chamber, these compartments being connected whereby the hot air will pass from one to another until it will finally enter a distributing-chamber within the inclosing casing, the cold air being fed into water-leg 25 chambers, thence passing into like chambers on each side of the fire-box and across the top of the combustion-chamber, tubular bars extending through the bottom of the fire-box and serving either as grate-bars or to support 30 grate-bars and opening outwardly through the front of the casing and inwardly in the rear of the bridge-wall, their front open ends being adapted to be more or less closed or opened and shut by a slide, whereby 35 when open they operate as a check-draft. A door is provided to clean out the several smoke-flues and cause the soot, &c., to be collected in a chamber in the rear of the ash-pit, whence they can be removed through a 40 door into the ash-pit. It is constructed as follows, reference being had to the accompanying drawings, in which—

Figure 1 is a front elevation of the heater. Fig. 2 is a vertical cross-section thereof. Fig. 45 3 is a vertical longitudinal section thereof.

Upon a base vertical walls 2 are erected connected by an arched top or crown-sheet, the walls constituting the sides of the ash-pit 3, fire-box 4, and combustion-chamber 5. 50 A bridge-wall 6 and a bar 7 upon the front of the casing 8 constitute the support for the tubes 9, which serve either as grate-bars or

as a support for grate-bars 10, and a slide 11 operates to open or close their front ends to permit or shut off or regulate a cold-air draft 55 through them. There are three vertical parallel walls 2, 12, and 8, which are separated a suitable distance, the distance between the walls 2 and 12 being about double that between the walls 8 and 12. Between the vertical walls 2 and 12, about on a level with the pipes 9, are perforated partitions 13, and below these partitions are air-chambers A, which are supplied with fresh air by the pipes 14, which have their inner ends to open into the 60 chambers and their outer ends open to the outside atmosphere. The air upon entering the chambers A through the pipes 14 rises through the partitions 13 into the air-chamber 15 above, where it is still further heated 65 by contact with the vertical walls 2 of the fire-chamber. At the top of the chamber 15 is a horizontal perforated partition 16, through which some of the heated air passes into the chamber 26. This partition extends only 70 half-way across the top of the chamber 15, while the remaining half of the chamber is open, so the heated air which does not pass through the partition 16 will pass into the chamber 25 above the top of the crown-sheet 75 80 a, and thus become highly heated. This chamber 25 is open at its lower end to the chamber 15, so that when the air in this chamber 25 becomes highly heated a portion of this air will pass through the partition 16 85 into the chamber 26. The arch 17 forms the top of the chamber 25, and above this arch 17 is a second one 19, and between these two arches 17 and 19 is formed the smoke-flue 20, which is open at the rear to the 90 combustion-chamber and at the front to the second smoke-flue member 21, between the arches 22 and 23, which opens rearwardly into the smoke-pipe 24, (dotted lines.) In this manner three hot-air compartments 25, 95 26, and 27 are created by the intermediate smoke-flues, and these are connected by pipes 30, as shown by the dotted lines in Fig. 2, whereby the air from the pipes 14 is heated and conducted from one compartment to another into the compartment 27, whence it is distributed through as many pipes 28 as may be deemed advisable to the rooms to be heated. A door 29 permits access to the smoke-flues 100

for cleaning the soot, &c., falling down into the chamber 30, whence it can be removed through the door 31 in the rear wall of the ash-pit. It will be seen that this dividing of the air-chamber into compartments 25 26 27 by the intermediate smoke-flues, the sides of which constitute the walls of the air-compartments, gives the largest area of heating-surfaces and largely increases the utility of the apparatus. It will also be seen that while "air" only is spoken of in the descriptive part hereof of the same apparatus can be used for hot-water or steam heating.

It will be seen that the slide 11 regulates the amount of cold air flowing through the tubes 9, so that when the usual direct-draft opening in the ash-pit door is closed and the slide 11 is opened the flow of cold air into the combustion-chamber in the rear of the bridge-wall and through the smoke-flues will operate as a check-draft and be very effective.

What I claim as my invention, and desire to secure by Letters Patent, is—

1. In a heater, the three vertical parallel walls 2, 8 and 12, the combustion-chamber formed between the inner walls 2, and the smoke-flues 17 and 23 extending from this combustion - chamber, combined with the chambers A between the walls 2 and 12, the perforated partitions 13 at the top of the

chambers A, the hot-air chamber 15 between the walls 2 and 12, the hot-air chamber 25 over the crown-sheet and connecting with the chamber 15, the hot-air chamber 26, the perforated partition 16 between the chambers 26 and 15, and the hot-air chamber 27 arranged above the chambers 25, 26, and connected therewith, the parts being arranged to operate substantially as shown. 35

2. In a heater, the three vertical walls 2, 12, and 8, extending parallel with each other, the hot-air chambers formed below the level of the grate, and upon each side thereof, the chamber 15 formed between the walls 2 and 12 and connected with the chambers A at its lower ends, the perforated partitions 13 arranged between the chambers A and 15, the perforated partition 16 placed at opposite sides of the air-chamber 15, the hot-air chambers 25, 26 and 27 arranged parallel with each other, and connected together, combined with the smoke-flues 20 and 21 between said chambers 25, 26 and 27, substantially as shown and described. 40 45 50

In witness whereof I have hereunto set my hand this 12th day of June, 1899.

HIRAM J. WATTLES.
